UNITED STATES PATENT OFFICE.

EUGÉNIE COHENDOS, OF MORRISTOWN, NEW JERSEY.

DESIGN FOR A CABINET-WASHSTAND.

SPECIFICATION forming part of Design No. 31,611, dated October 3, 1899.

Application filed August 9, 1899. Serial No. 726,720. Term of patent 14 years.

To all whom it may concern:

Be it known that I, EUGÉNIE COHENDOS, a citizen of the Republic of France, and a resident of Morristown, in the county of Morris 5 and State of New Jersey, have invented and produced a new and original Design for a Cabinet-Washstand, of which the following is a specification, reference being made to the accompanying drawing, forming a part thereof.

10 The drawing is a perspective view showing my new design for a cabinet-washstand.

As shown in the drawing, the leading or characteristic feature of my design consists of the upright central rectangular part having main paneled doors, the upper rectangular part having smaller paneled doors than

the central rectangular part, and an unobstructed top and the laterally-projecting rectangular wings, one wing having three panels and an unobstructed top, and the other wing 20 having a large panel and two smaller panels and an unobstructed top.

Having thus described my invention, the following is what I claim as new therein and desire to secure by Letters Patent: 25

The design for a cabinet-washstand; substantially as shown and described.

EUGÉNIE COHENDOS.
